No. 703,604.

Patented July 1, 1902.

W. J. D. MAST.

SPIRIT LAMP.

(Application filed Aug. 17, 1901.)

(No Model.)

UNITED STATES PATENT OFFICE.

WILLIAM J. D. MAST, OF BUFFALO, NEW YORK, ASSIGNOR TO THE BUFFALO MANUFACTURING COMPANY, OF BUFFALO, NEW YORK.

SPIRIT-LAMP.

SPECIFICATION forming part of Letters Patent No. 703,604, dated July 1, 1902.

Application filed August 17, 1901. Serial No. 72,374. (No model.)

To all whom it may concern:

Be it known that I, WILLIAM J. D. MAST, a citizen of the United States, residing at Buffalo, in the county of Erie and State of New York, have invented new and useful Improvements in Spirit-Lamps, of which the following is a specification.

This invention relates to that class of spirit-lamps which are provided with regulating means or caps for more or less obstructing the flame-openings to control the volume of the flame. In the use of such lamps it has been found that where the air-supply for the flame is not shut off or diminished when the regulator or cap is operated to diminish or extinguish the flame the flame is free to burn under the cap and in the air-supply passages, thus causing inconvenience and at times damage, as the flame is thereby directed downward and out at the bottom of the air-passages, which being located in the lower part of some lamps is apt to ignite or scorch the supporting object on or over which the lamp is placed.

The principal object of this invention is to provide means for controlling the air-supply operated when the regulator or cap is operated, to decrease or cut off the air-supply as the flame is decreased or cut off, and to increase the air-supply as the regulator or cap is moved to increase the flame.

Another object is to provide an air-supply controlling means operatively connected with and operated by the flame-regulator.

A further object is to so arrange the air-supply openings for the flame and so construct the regulating-cap that it will control the air-supply openings as well as the flame-opening.

A further object is to provide the lamp with a flame-regulating cap operated by a handle longitudinally movable toward and from the lamp or radially with respect to the lamp as contradistinguished to sidewise or circumferentially.

A still further object is the production of a lamp of the character stated of simple and improved construction.

In the accompanying drawings, Figure 1 illustrates in an elevational view a spirit-lamp embodying the invention. Fig. 2 is a

vertical sectional elevation. Fig. 3 is a plan view with the top broken away to show the regulating-cap, which is shown closed. Fig. 4 is an inverted horizontal section on the line 4-4 of Fig. 2, showing the cap open by full lines and partly closed by dotted lines. Fig. 5 is a horizontal sectional view of a modified construction.

Like letters of reference refer to like parts in the several figures.

Referring to the drawings, A indicates the lamp body or font, which may be of any desired or usual construction; B, the usual flame and filling opening in the font-top; C, the asbestos or the like absorbent filling, and D the perforated or wire-gauze diaphragm over the asbestos filling and extending across the flame-opening and on which the flame burns. These parts are all common.

E indicates an upright flange or wall on the font surrounding the flame-opening and provided around the same with air-supply openings e for admitting air to the flame.

F indicates a cover, which has a substantially upright wall f, rising from an outwardly-extending or enlarged portion f' of the lamp-font, and an annular substantially horizontal inwardly-extending top plate or flange F', the central opening F² of which is above and substantially the same size as the flame-opening B in the font.

Extending laterally outward from the lower portion of the upright flange E and below the air-openings e therein is an annular plate or partition G, which is secured at its outer edge to the upright wall f of the cover. This diaphragm divides the space between the top of the font and the top of the cover into a lower annular air-space H and an upper annular chamber I, in which the regulating-cap, presently to be described, is located. The annular air-space H communicates with the external air by means of openings h in the lower part of the upright wall f and with the cap-chamber by means of openings i in the annular plate G. Thus it will be seen that the air-supply for the flame to reach the air-openings e in the upright flange surrounding the flame-opening must pass through the opening i.

Within the regulator-chamber—that is, be-

tween the horizontal partition G and the top cover-plate F'—is a flame regulator or cap, which is shown to comprise two sections J and J', which are mounted to move toward 5 and from each other over the upright flange E, surrounding the flame-opening of the font, and between the same and the opening in the cover-top to more or less or completely close or 10 open communication between said openings, and thus extinguish or regulate the flame.

As before stated, to effectually regulate or extinguish the flame the air-supply thereto should be controlled as well as the flame-opening, and for this purpose each regulator- 15 cap section is provided with a substantially semicircular depending flange, (indicated, respectively, at *j* and *j'*.) By moving the cap-sections to open the flame-opening and permit a large or full flame the flanges are carried 20 to a position over or outwardly beyond the openings *i*, and thus permit the air to pass through the same to the air-opening *e*; but when the cap-sections are moved to partially or completely close the flame-opening 25 the flanges *j* and *j'* are carried to a position over the openings *i* or between the openings *i* and *e* and either partially or completely 30 shut off the openings *e* from communication with the external air through the openings *i*, depending upon the extent of movement of the cap-sections. To further insure the necessary control of the air-openings and guarantee 35 a nice regulation, each flange *j* and *j'* carries at its bottom an outwardly-extending horizontal flange, (indicated at *j*² and *j'*²), which slide over and cover or uncover the 40 openings *i*. The horizontal flanges *j*² *j'*² also provide flat supporting and sliding surfaces for the cap-sections and for this purpose slide on the horizontal plate or partition G.

The cap-sections may be of any desired configuration and provided with any suitable operating means to cause them to approach toward and recede from each other. Their 45 construction and the construction of the operating means (shown in Figs. 1 to 4) are as follows: The horizontal plate of each cap-section has in its front or inner edge a substantially semicircular notch K, which when 50 the sections are separated to the full extent of their movement completely expose the burner-opening. One cap-section—as, for instance, J—has its side portions at *k* extended forwardly, so as to overlap and rest upon 55 the opposite section when separated to their full extent, and each section at its opposite ends is provided with depending straight guide-flanges, (indicated at *k'* *k'*², respectively,) which may be and preferably are 60 extensions of the semicircular air-regulator flanges *j* and *j'*. The flanges *k'* of the cap-sections J are outside of the flanges *k'*² of the section J', the flanges mutually assisting in maintaining the cap-sections always in alignment. The flanges *k'* and *k'*² also aid the 65 flanges *j* and *j'* in preventing entrance of air to the openings *e*. The guide-flanges *k'* of

the section J do not join the semicircular flange *j* tangentially, as is the case with the flanges *k'*² of the other cap-section, but extend farther rearward and have the inturned portions *k*³, forming pockets to receive the ends of the other cap-section J' in order to admit of the sections being moved to completely close the burner-opening, which could not be done if the guide-flanges of each section joined the semicircular flange tangentially. L indicates guide and retaining strips located between the guide-flanges *k'* and the upright wall *f* of the cover and preferably secured to the latter. This wall at opposite sides is provided with slots or openings *l* and *l'*, through which the cap-sections are adapted to project when moved outwardly or away from each other. 75 80 85

For simultaneously moving the cap-sections in opposite directions one of them—for instance, J'—has secured thereto an operating-rod M, projecting through the opening *l'* and sliding in a bearing *m*, secured to the outside 90 of the cover-wall *f*. At its outer end the rod is provided with a suitable handle *m'*.

N indicates a lever fulcrumed to the top plate F' at *n* and provided with a slot *n'*, into which projects a stud or pin *n*², secured to the cap-section J'. O indicates a similar lever fulcrumed at *o* to the top plate and provided with a slot *o'*, into which projects a stud or pin *o*², secured to the other cap-section J. The pins *n*² and *o*² are preferably headed to 100 prevent disengagement from the slots. 95 105

P is a link pivoted at one end to one of the levers N O between its fulcrum and its connection with the cap-section and pivoted at its other end to the other of the levers N O 110 beyond its fulcrum or on the side thereof opposite to its connection with the cap-section. By this arrangement when the cap-section J' is moved in or out by the operating-rod M the other cap-section J is moved in the opposite direction through the medium of said levers and link. 115 120 125

The lamp disclosed and above described is especially adapted for use in connection with a chafing-dish, kettle, or the like, and, as well known, such lamps are usually loosely supported in a ring or cup-shaped bracket beneath the dish or kettle. It is therefore apparent that in operating the regulator-cap by the push-rod M it is not necessary to hold the lamp from turning in its support, as is apt to be the case where a lever or sidewise-movable operating device is employed. 130 135

For convenience in manufacture the cover F is preferably made separate from the lamp-font and is secured thereto by turning the lower edge of the upright wall under the outwardly-projecting portion of the font or body. The sectional cap and its operating means are carried by the cover and are preferably assembled and arranged therein before the horizontal plate G is secured in place. 140 145

In Fig. 5 is illustrated a modified construction of means for causing the opposite move-

ment of the regulator-cap sections. In this instance one of the cap-sections is provided with a toothed rack Q and the other section is provided with an opposing toothed rack R, between which and meshing with both racks is a pinion S, journaled on a stud or the like, secured to the top cover-plate. Preferably two sets of racks and two pinions are provided, as shown in Fig. 5, though the double construction is not absolutely necessary.

I claim as my invention—

1. The combination of a lamp provided with a flame-opening and with an air-supply, of a flame-regulator for more or less obstructing said flame-opening, means for regulating the air-supply, and connections whereby one of said regulating means is operated upon the operation of the other, substantially as set forth.
2. The combination with a lamp provided with a flame-opening and an air-supply opening, of a flame-regulator for more or less obstructing said flame-opening, and means operated by the flame-regulator for controlling said air-supply opening, substantially as set forth.

3. The combination with a lamp provided with a flame-opening and an air-supply opening, of a flame-regulator for more or less obstructing said flame-opening, and means carried by said flame-regulator for more or less obstructing said air-supply opening, substantially as set forth.

4. The combination with a lamp provided with a flame-opening and air-supply opening, of a sectional flame-regulator for more or less obstructing said flame-opening, and parts carried by said regulator-sections and controlling said air-openings, substantially as set forth.

5. The combination with a lamp provided with a flame-opening surrounded by a wall provided with air-supply openings, of a sectional flame-regulator provided with flanges

for controlling said air-supply opening, substantially as set forth.

6. The combination with a lamp having a flame-opening and a wall surrounding the same and provided with air-openings, of an annular plate surrounding said wall below said air-supply openings and provided with air-openings, and a sectional flame-regulator provided with flanges adapted to be moved to a position between said air-supply openings in the wall and said air-openings in the annular plate to regulate the air-supply, substantially as set forth.

7. The combination with a lamp having a flame-opening, and a wall surrounding the same and provided with air-supply openings, of an annular plate located below said air-supply openings in the wall and having air-openings, and a sectional flame-regulator provided with vertical flanges adapted to be moved to a position between said air-supply openings and the openings in the annular plate, and horizontal flanges extending outwardly from the lower ends of said vertical flanges, substantially as set forth.

8. The combination with a lamp having a flame-opening, of a sectional regulator-cap the sections of which are slidable toward and from each other, an operating-rod for said regulator arranged radially relative to said lamp and connected to one of said cap-sections and movable lengthwise to operate the same, means for guiding said rod, and connections between said regulator-cap sections for causing the operation of both regulator-cap sections when said operating-rod is actuated, substantially as set forth.

Witness my hand this 14th day of August, 1901.
